(57) **CLAIM**

The ornamental design for a mop brush for cleaner, as shown and described.

DESCRIPTION

FIG. 1 is a front perspective view of a mop brush for cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view in an environment of use;

FIG. 9 is another front perspective view in an environment of use;

FIG. 10 is an exploded view of FIG. 8 showing a water bottle of the mop brush separated from a main body thereof;

FIG. 11 is an enlarged view of the encircled portion 11 in FIG. 1;

FIG. 12 is an enlarged view of the encircled portion 12 in FIG. 2;

FIG. 13 is an enlarged view of the encircled portion 13 in FIG. 4;

FIG. 14 is an enlarged view of the encircled portion 14 in FIG. 7;

FIG. 15 is an enlarged view of the encircled portion 15 in FIG. 9; and,

FIG. 16 is an enlarged view of the encircled portion 16 in FIG. 10.

The even-dash broken lines illustrating portions of the mop brush form no part of the claimed design. The dot-dash

(Continued)

broken lines encircling enlargement portions of the claimed design form no part of the claimed design.

1 Claim, 16 Drawing Sheets
